MIXING DEVICE

Abraham M. Herbsman, Huntington Park, and Rodney B. Campbell, Walnut Park, Calif., assignors, by direct and mesne assignments, to Industrial Patents, Ltd., Los Angeles, Calif., a Corporation of California

Application March 6, 1933. Serial No. 659,776

4 Claims. (Cl. 137—111)

Our invention relates to mixing devices and particularly to a novel device for receiving a plurality of fluids and discharging a homogeneous mixture of these fluids.

Although useful in many arts, the mixer of our invention is particularly adapted to use in the petroleum industry for mixing various chemicals to be injected into a pipe line carrying a petroleum emulsion under high pressure.

10 In the petroleum industry, oil is frequently taken from wells in the form of an emulsion of oil and water, it being necessary to separate the water from the oil prior to the refining process. The process usually employed for 15 treating emulsified oil includes mixing a chemical with the emulsion which tends to coagulate the dispersed phase so that the latter will readily separate out by gravity.

19 The chemical usually used for treating oil emulsions consists of two liquids which, for maximum effectiveness, should be freshly mixed just before being injected into the pressure line carrying the oil and water emulsion.

It is an object of our invention to provide a 25 mixer for receiving a plurality of separate chemicals under pressure and discharging a homogeneous mixture of said chemicals.

29 A further object of our invention is to provide a mixer which is adapted to receive a continuous supply of chemicals and discharge a continuous mixture of these chemicals.

The manner of accomplishing the foregoing objects, as well as further objects and advantages, will be made manifest in the following description, taken in connection with the accompanying drawing, in which:

Fig. 1 is a plan view of a preferred embodiment of our invention partly broken away to show the construction of the interior thereof.

40 Fig. 2 is a sectional view taken on the line 2—2 of Fig. 1.

Figs. 3 and 4 are horizontal sectional views taken on the lines 3—3 and 4—4 respectively of Fig. 2.

45 Referring specifically to the drawing, a mixer 10, comprising a preferred embodiment of our invention, includes a single casting 11 formed to provide a closed shell 12 having threaded inlet openings 13 and 14 and a threaded outlet opening 15 as shown in Fig. 2. The interior of the shell 12 is divided horizontally by upper and lower walls 18 and 19 respectively, the wall 18 being connected to the top wall of the shell 12 by a transverse wall 20 to form inlet chambers 21 and 22, ports 23 and 24 being formed in the

wall 18 in communication with the chambers 21 and 22 respectively. Extending downwardly from the wall 18 into the space between the walls 18 and 19 is an annular wall 26 which supports a horizontally disposed cup-shaped wall 27, the latter forming a mixing chamber 28. The space between the wall 27 and the lower wall 19 constitutes another mixing chamber 29.

Extending downwardly from the cup-shaped wall 27 into the chamber 29 is an annular skirt 30. Formed in the wall 26 is a plurality of holes 31 which allow communication between the chambers 28 and 29, these holes extending downwardly and being disposed spirally relative to the vertical axis of the mixer 10.

The wall 19 has a central hub 33, an upper portion of which extends into the skirt 30. The hub 33 has a central opening 34 therethrough in which a core 35 is provided, the latter being supported from the walls of the opening 34 by helically disposed mixing blades 36.

The lower portion of the shell 12 is formed to provide a hemispherical bottom wall 38, the space between the walls 38 and 19 comprising a third mixing chamber 39. Disposed within the chamber 39 is a cup 40 which lies close to the wall 38 and is supported thereon by webs 41, the latter being separated by passages 42 leading from the chamber 39 to the discharge opening 15 as shown in Fig. 4.

Operation

A plurality of liquids is thoroughly mixed by the mixer 10 of our invention in the following manner: The inlet chambers 21 and 22 are each supplied with a liquid from any suitable source of supply by means of inlet pipes 45 and 46, the latter being received by the threaded openings 13 and 14 respectively of the shell 12. The liquids to be mixed pass from the chambers 21 and 22 through the openings 23 and 24 into the chamber 28 where the first mixing takes place. From the chamber 28 the mixture passes through the holes 31 into the chamber 29, the mixture being further agitated by a rotary motion set up in the chamber 29 as the liquid passes through the spirally disposed holes 31. From the chamber 21 the mixture passes under the skirt 30 and downward through the opening 34 of the hub 33. As the mixture passes the helical blades 36 into the cup 40 further agitation occurs from the rotary motion set up by the angularity of the blades 36, the direction of rotation of the fluid in the cup 40 being opposite to the rotation in the chamber 29. From the cup 40 the mixture is forced through

the passages 42, into the discharge opening 15, and is delivered to any desirable destination, such as the aforementioned oil pipe line, by means of a suitable discharge pipe 47.

5 It is thus seen that the mixer of our invention is capable of producing a thorough mixture of component fluids, and that our device is simple to construct, void of moving parts and particularly well adapted to receive fluids under pressure.

10 We claim as our invention:

1. A liquid mixer comprising a body having two inlet and one outlet openings, a primary central mixing chamber connected by two closely adjacent ports with said inlet openings, an annular mixing chamber connected by spirally disposed ports with said primary central mixing chamber, and a passage leading from said annular mixing chamber to said outlet opening.

15 2. A liquid mixer comprising a body having two inlet and one outlet openings, a primary central mixing chamber connected by two closely adjacent ports with said inlet openings, an annular mixing chamber connected by spirally disposed ports with said primary central mixing chamber, and a passage leading from said annular mixing chamber to said outlet opening.

20 3. A liquid mixer comprising a body having two inlet and one outlet openings, a primary central mixing chamber connected by two closely adjacent ports with said inlet openings, an annular mixing chamber connected by spirally disposed ports with said primary central mixing chamber, a secondary central mixing chamber, connected by a radial passage with said annular chamber, and a passage leading from said secondary central chamber.

3. A liquid mixer comprising a body having two inlet and one outlet openings, and a series of intermediate chambers, said chambers being successively centrally disposed and annularly disposed, and connected by radial passages, said inlet openings connecting with a chamber at one end of said series and said outlet opening with a chamber at the other end of said series.

4. A liquid mixer comprising a body having two inlet and one outlet openings, a pair of annular chambers formed separately in said body, a pair of centrally disposed chambers in said body, said inlet openings discharging at adjacent points into one of said centrally disposed chambers, passage means for conducting fluid thus discharged into said centrally disposed chamber to one of said annularly disposed chambers in a manner to give this fluid a rotary motion, passage means for conducting said rotating fluid into a second centrally disposed chamber so as to again give a rotating motion to this fluid, passages connecting said second centrally disposed chamber with a second annular chamber, and passage means connecting said second annularly disposed chamber with said outlet opening.
